TRAIN ORDER DELIVERY DEVICE

Wayne Earl Robertson, Westby, Wis.

Application September 6, 1940, Serial No. 355,644

10 Claims.

(Cl. 258—2)

Railroad trains are operated on written orders from the train dispatcher to the trainmen, delivered in person from time to time during each run. The average cost of stopping and starting a train is estimated at approximately five dollars (\$5.00), the cost increasing with the speed and the weight of the train. The time lost in stopping for orders and getting up to speed again interferes not only with operating economy but also with schedules, and increases the chance of accident. The growing use of faster schedules has made it more and more desirable or necessary to deliver train orders without stopping, or even slowing down the train, and has also greatly increased the difficulty of delivering the required number of orders to a train.

Each engineer and conductor, and sometimes the flagman on the rear end, must receive a separate order, and these men are unavoidably located at different places in the train. The engineers are further from the ground than the conductors or the flagman, and the two engineers on a double header are only about a locomotive length apart. These conditions have made the delivery of orders on a speeding train uncertain, difficult and dangerous.

The principal object of this invention is to make the delivery of train orders certain, easy and safe. Generally speaking, this is accomplished by mounting each separate folded order on a looped cord hung on an order fork, to which the cord is hitched for ready detachment when the order strikes the trainman's hand as he passes. The supports for the forks, and therefore the orders, are arranged to hold the order in a definite relation to the window sill, for example, of the engineer's cab, or the car platform, as the case may be. The orders for the engineer are at different elevations from the orders for the conductor and flagman, the order for the second engineer being above that for the first, engineer and dropping to the appropriate position immediately after the first engineer receives his order, and the order for the flagman at the rear end being above the order for the conductor, and dropping into position after the conductor receives his order.

The receipt of the order by the first engineer, or by the conductor, operates a trip or trigger supporting the companion order in raised position, and allows it to immediately drop into the appropriate position for receipt by the following engineer or the flagman. Thus each man merely holds his hand in the appropriate position, and the orders are delivered to each in turn as the

train speeds by the station. The orders are set on the supports in advance of the expected train, and no excitement or error of the station operator will cause a failure of delivery or injury to the man receiving the order.

Additional objects will become apparent from the following detailed description and from the drawings, in which

Fig. 1 is a schematic view illustrating the dis-
position of my device with respect to a train;

Fig. 2 is a diagrammatic illustration showing the position of the order delivery arms after all
except the last order has been removed;

Fig. 3 is a detailed perspective view of the
order delivery device;

Fig. 4 is a partial end view of the upper deliv-
ery device showing a method of attaching the
second order delivery arm to the first order de-
livery arm;

Fig. 5 is a detailed illustration of my order
delivery device, showing the position of the unit
after the removal of a train order from the first
delivery arm;

Fig. 6 is a detailed perspective illustration of
the base; and

Fig. 7 is a diagrammatic representation of the
staff.

Referring to Fig. 1, my assembled train order
delivery device comprises a base, generally design-
ated 11, a staff 12, a staff extension 13, an upper
order delivery unit generally designated 14, and
a lower order delivery unit generally designated
16. The base 11, shown more clearly in Fig. 6,
consists of a pipe 17 having a solid point 18 for
ease of installation. The upper end of the base
is provided with aligned grooves 19. A collar 21
is attached to the upper portion of the base in
any desired manner, as by welding,—its loca-
tion on the base being such that the upper end
of the pipe 17 extends slightly beyond the upper
portion of the collar 21.

Two parallel vertically disposed flanges 22 are
formed integrally with collar 21, and are pro-
vided with aligned openings 23 in their extrem-
ities. A cap 24 is also provided having internal
and external dimensions approximately equal to
those of the collar 21. The cap carries a ver-
tically disposed flange 26, adapted to be received
between the vertically disposed flanges 22 on
collar 21, and is supported between the flanges
22 by a pin 27 passing through the openings
23 and a corresponding opening through the
flange 26, in such manner that the cap 24 may
be swung into closed position over the base to
prevent the accumulation of foreign matter with-

in the pipe 17. If desired, the collar 21 and the cap 24 may be provided with cooperating lugs 28 having openings formed therein to permit locking the cap in its closed position.

The base 11 is driven into the ground a suitable distance from the tracks, leaving only a small portion of the base extending above the level of the ground. The staff 12 is hollow and has an external diameter slightly smaller than the internal diameter of the base 11. Vertical 10 adjustment of the staff is secured by providing a series of the vertically spaced aligned openings 29 in the lower portion of the staff 12, which are adapted to receive a key 31, secured to the staff by a chain 32. The key 31 rests in the 15 grooves 19 in the upper portion of the base 11 when the staff 12 is inserted therein, so that the overall height of the staff 12 is controlled 20 by the position of the key 31 in the staff 12. This construction also prevents rotation of the staff relative to the base, and permits its removal without difficulty.

The staff extension 13 telescopes into the staff 12, which is provided with a thumb-screw 33 in its upper portion to hold the staff extension 25 in an extended position. The upper train order delivery unit 14 is attached to the upper portion 30 of the staff extension 13, and comprises a frame generally designated 34, a rotatable shaft 36 journaled in the frame 34, an upper delivery arm, generally designated 37, and a lower delivery arm, generally designated 38, associated with the shaft 36, and a trigger 39 movably associated with the frame 34.

Referring to Fig. 3, the frame 34 consists of 35 two sections, a leg 41 of the left-hand section cooperating with leg 42 of the right-hand section to define an opening having an inside diameter slightly less than the outside diameter of the staff extension 13. The frame may be attached to any portion of the staff extension 13 by inserting the extension in the opening defined by the legs 41 and 42, moving the frame to the desired position, and clamping the legs together with bolts 43, which extend through aligned openings in the legs 41 and 42.

The left section consists of five legs, each extending laterally from its adjacent legs. A leg 44 extends outwardly from the rear end of leg 41; leg 46 extends rearwardly from the outer end of leg 44 parallel to leg 41; leg 47 extends outwardly to the left from the rear end of leg 46 parallel to leg 44; and leg 48 extends inwardly from the outer end of leg 47 parallel to leg 41. The inner ends of legs 41 and 48 are in substantially the same vertical plane.

The right-hand section comprises a leg 49 extending outwardly to the right from the rear end of leg 42, and leg 51 extending rearwardly from the outer end of leg 49 parallel to legs 48, 46, 42 and 41. Leg 52 extends outwardly to the right from the inner end of leg 42, substantially parallel to leg 49 of the same section. The outer portion of leg 49 is angularly disposed with respect to the vertical plane of the remainder of the arm, as indicated at 53.

One arm 54 of the shaft 36 is journaled in the legs 46 and 51, and projects outwardly beyond arm 51. The other arm 56 of the shaft 36 extends inwardly adjacent to leg 46 from the arm 54, and has a tube 57 attached to its extremity.

A collar 58 fits loosely over the projecting portion of the arm 54 of the shaft 36, and carries a permanently fixed laterally extending tubular extension 59 in which is fixed an arm 61. The 70 75

outer section of the arm 61 has a tube 57', similar to tube 57, attached to its outer extremity.

The outermost position of the collar 58 on the shaft 36 is fixed by a pin 62 extending through a transverse opening in the shaft 36, and projecting laterally from the shaft in both directions. Relatively wide diametrically opposed grooves 63 are formed in the outer end of the collar 58, the projecting ends of the pin 62 lying within these grooves. The inner end of the collar 58 is in contact with the face of the frame leg 51. By this construction it may be seen that I have provided a lost motion linkage between the shaft 36 and the collar 58. The position and extent of the grooves 63, as well as the position of the pin 62 with respect to the leg 56 of the shaft 36 is such that the pin 62, acting against the edges of the grooves 63, will support the arm 61 at an angle of about 30° from the vertical when the arm 56 is substantially horizontal, and will allow the arm 56 to fall to a vertical position when the arm 61 falls to a horizontal position. A spring catch 64 is attached to the under side of the arm 61, and is positioned to engage the leg 53 of the frame 34 when the arm 61 is allowed to fall to a horizontal position.

The trigger 39 is formed with a closed loop at one end which engages the eye of an eye-bolt 66, attached to the inner portion of the frame leg 41. The length of the trigger 39 is greater than the distance between the frame legs 41 and 48, and is moved to its operative position by placing the free end of the trigger on the upper portion of the leg 48. In this position the trigger 39 will prevent the downward movement of the arm 56 beyond an approximately horizontal position.

Order forks, generally designated 67, comprise an arm 68, to one end of which is clamped angularly extending resilient fingers 69. The clamp consists of two triangular shaped plates, designated 71, which, in their assembled relation, define receiving openings for the end of the arm 68 and the fingers 69. The plates 71 may be drawn together by bolts 72, thereby securing the parts of the order fork 67 in fixed relation. A flat spring 73 is secured to one of the plates 71, as by a screw 74, and is shaped to remain normally in resilient contact with the plate. The tube 57 receives the end of the order fork arm 68, a thumb screw 76 being provided on the tube to retain the arm in position.

The lower order delivery unit 16 is generally similar to the upper unit previously described, but is normally attached to the staff 12 instead of to the staff extension 13. Furthermore, as the lost motion device for the upper delivery arm is not necessary on this unit, the collar 58, tubular section 59, and the arm 61 described in connection with the upper unit may be replaced by a leg 11 formed integrally with the shaft 36. The leg 11 should be disposed at an angle of greater than thirty but less than ninety degrees above the leg 56. The catch 64 may also be eliminated from this unit, if desired.

The operation of my device may be best described in connection with a high-speed passenger train employing two locomotives, as both engineers, the conductor and the flagman must receive orders. To attach the orders to the forks each end of a section of string 78 is tied to the order in a manner well known in the art, and the string, now forming a closed loop, is passed over notches 79 in the ends of the fingers 69, the order being located approximately midway be-

tween the extremities of the fingers 69. Both sections of the string 78 are drawn together, bowing the fingers 69, and are passed between the spring 73 and the plate 71, the spring serving to hold the cord 78 taut.

The same process is performed for each fork, and when completed the forks may be secured in the tubes 51 and 51' by tightening the corresponding thumb screw.

The cords 78, attaching the orders to forks intended for attachment to the first or lower arms of each unit, should be cut sufficiently long to provide a loop extending beyond the spring clip 73. The upper unit 14 is placed in operative position by raising the arm 56 above the horizontal, placing the loop of the string 78 around the trigger 39, and placing the trigger 39 in position with its free end resting upon the upper edge of the frame leg 48. With the trigger in this position the lower arm 38 will be in a substantially horizontal position and the upper fork will be held in a raised position, but in the same quadrant with the lower fork. A lower unit 16 is prepared for operation in a similar manner.

The position of the lower unit 16 on the staff 12 is adjusted, either by moving the unit upon the staff or by changing the position of the key 31, to bring the order into easy reach of the conductor. The upper unit 14 is generally clamped to the top of the staff extension 13, and is raised to about the level of a locomotive cab window by moving the staff extension 13 upwardly, its position being fixed by tightening the thumb screw 33.

To obtain the order the engineer on the first locomotive extends his arm from the cab window, his hand passing between the fingers 69 of the lower order fork of the upper unit. The looped cord 78 strikes his hand or forearm, and is pulled free of the resilient fingers 69 and the spring catch 73. The cord also pulls the trigger 39 free of the frame leg 48, thereby releasing the cord and the lower delivery arm 38. Practically all of the weight of the movable parts of the unit act to swing both delivery arms downwardly immediately with considerable velocity until the upper delivery arm 37 strikes the frame leg 52. The spring catch 64 engages the arm 52 to prevent vertical movement or rebound of the delivery arm 37. The lower arm is not immediately checked in its downward movement, however, due to the lost motion device on delivery arm 37, and will continue to move downwardly until it reaches an approximately vertical position well out of the way of the engineer on the second locomotive and the mail pouch catcher. The upper arm 37 assumes a position substantially identical to that formerly assumed by the lower arm 38, and within easy reach of the engineer on the second locomotive.

It may be seen that if the train is moving at a high rate of speed and the engineers are only about a locomotive's length apart, the upper order fork must assume the horizontal position with considerable rapidity. This rapid movement is provided by the lost motion device, for the upper arm is in the same quadrant as the lower arm and as close to a horizontal position as practical, so that both arms exert close to the maximum possible rotative force on the shaft 36 the moment the trigger 39 is released.

The conductor of the train may reach from a vestibule window and easily secure the order held by the lower delivery arm of the lower unit, which will release the trigger 39', in a manner similar to

that described for the upper unit. The lost motion device and catch, as previously mentioned, are not necessarily on this unit, as the distance between the conductor and the flagman is usually sufficiently great to permit the second order delivery arm to assume its operative position in ample time. The lower unit is also generally lower than the mail pouch catcher.

Unless other orders are to be delivered to a subsequent train within a short time, the staff extension 13 may be retracted into the staff 12 and the entire assembly removed from the base 11. This is desirable, as obstructions on a railway station platform are liable to constitute a safety hazard. It is, of course, unnecessary to employ all four order forks, and practically any combination may be used. If, for example, orders are to be delivered only to the engineer and the conductor, only one arm of the upper and one arm of the lower unit need be employed. In this case it is immaterial which of the two arms on each unit are used.

The foregoing description has been made for the purpose of illustration only, and as it is obvious that many modifications may be made without departing from the true scope and spirit of my invention I do not wish to be limited to the precise details described except as defined by the appended claims.

I claim:

1. In apparatus for delivering train orders, a frame, a rotatable shaft carried by the frame, two order delivery arms carried by the shaft arranged at an angle to each other, with one following the other in rotation, means for holding the following arm in raised position while the leading arm is in order delivering position including a trigger, the trigger being directly actuated by the delivery of an order carried by the leading arm, means rigid with the frame to stop the second arm in order delivering position, and means to prevent rebound from that position, said means including a clip on the following arm disposed to engage a portion of the frame.

2. In an apparatus for delivering train orders, a base, a removable staff in said base including upper and lower sections adjustable with respect to each other, a frame adjustable along the lower section, a second frame carried by the upper section, a rotatable shaft carried by each frame, first and second order delivery arms carried by each shaft, order delivery forks attached to the arms, flexible members each attachable to an order associated with each order delivery fork, a movable trigger cooperating with the frame for temporarily holding each first arm in order delivering position and directly actuated by the corresponding flexible member, and a stop rigid with the frame to catch the second arm in order delivering position.

3. A train order delivery device including a frame, a shaft rotatably mounted on the frame, leading and following order delivery arms mounted in spaced relation on the shaft one above the other and arranged for rotation in substantially vertical planes, a movable trigger supported by the frame and cooperating therewith for holding the leading arm in order delivery position, and a looped order holding cord associated with the lower order delivery arm, the trigger being inserted in the looped order holding cord whereby delivery of an order directly actuates the trigger and releases the arms for rotation.

4. A train order delivery device including a frame, a shaft rotatably mounted on the frame,

a leading order delivery arm rigidly attached to the shaft and adapted to receive an order fork, a following order delivery arm adapted to receive another fork, means interconnecting the following arm to the shaft, said arms being angularly spaced from one another and arranged for rotation in substantially vertical planes, and a movable trigger interposable between the leading arm and the frame for supporting the leading arm for order delivery position and adapted for direct connection to the order holding cord associated with the leading arm, the connecting means between the following arm and the shaft including a lost motion device whereby restraint of the following arm in order delivery position will not immediately restrain movement of the leading arm.

5. In a train order delivery device, a frame, a horizontal shaft rotatably mounted on the frame, a leading order delivery arm rigidly attached to the shaft, a following order delivery arm rotatably supported by the shaft, each of said arms being adapted to support an order fork, means movable with the shaft and engaging the following arm for defining a minimum angular displacement between the arms of less than 90°, the maximum displacement between the arms being not less than 90° whereby downward rotation of the following arm may be abruptly stopped without immediately restraining rotation of the shaft.

6. A train order delivery device comprising a frame, a rotatable shaft carried by the frame, upper and lower order delivery arms carried by the shaft, a removable flexible member associated with each of the arms and adapted for attachment to an order, a trigger movably mounted directly on said frame and cooperable with the frame for holding the lower arm in order delivering position and the upper arm in raised position, the flexible member associated with the lower arm directly engaging the trigger whereby movement of the flexible member will release said trigger for releasing said arms for rotation, and means to stop the upper arm in order delivering position.

7. A train order delivery device comprising a frame, a rotatable shaft carried by the frame, upper and lower order delivery arms carried by the shaft, said arms defining an angle, a holding device movably mounted directly on said frame and cooperable with the frame for holding the lower arm in order delivering position and the second upper arm in raised position, order holding means movable with each arm and including an easily removable flexible member for holding an order, the flexible member on the lower order supporting arm directly engaging said holding device whereby in the delivery of an order tension on said flexible member positively removes said holding device to allow rotation of said arms, to bring said upper arm into order delivery position.

8. In a train order delivery device, a frame, a rotatable shaft carried by the frame, an order delivery arm attached to the shaft, a second order delivery arm carried by the shaft above the first arm but spaced therefrom and adapted to follow the first arm in rotation, a separate order holding device secured to each of said arms, the order holding devices being of the type employing a looped order holding cord, and a trigger movable directly on said frame and interposable between the first order delivery arm and the frame to retain said first order delivery arm in order delivery position, said trigger extending through a loop of the order holding cord associated with the lower delivery arm for releasing said trigger when said cord is removed from said order holding device.

9. In a train order delivery device, a frame, a rotatable shaft carried by the frame, an order delivery arm attached to the shaft, a second order delivery arm attached to the shaft, said second order delivery arm carried by the shaft above the first arm but spaced both laterally and angularly therefrom and adapted to follow the first arm in rotation, an order holding device secured to each of said arms, the order holding devices being of the type employing a looped order holding cord, a movable trigger directly on said frame and interposable between the first order delivery arm and the frame to retain said first order delivery arm in order delivery position, the trigger extending through a loop of the order holding cord associated with the lower order delivery arm when the latter is in order holding position whereby removal of the order and cord directly releases the trigger from holding the first-named arm for rotation, a stop rigid with the frame for halting the second order delivery arm in order delivery position, and means associated with the arm and frame for preventing rebound of said second arm from the stop.

10. In an order holding device, a staff, an upper frame member on said staff, an upper shaft journaled on said frame, upper and lower order delivery arms mounted on the end portions of said shaft, respectively, one on each side of said staff, a lower frame on said staff, a lower shaft journaled on said lower frame, upper and lower delivery arms mounted on the end portions of said lower shaft, respectively, order forks carried by said arms, a trigger directly connected to each frame for engaging the corresponding lower arm for holding said arms in elevated position, a flexible order supporting member for each fork, the flexible members for the lower forks engaging said triggers for releasing the same when the corresponding flexible member is released, said lower arms being on one side of said staff and the upper arms on the other, whereby interference between the arms of the upper and lower frames are prevented.

WAYNE EARL ROBERTSON.
